UNITED STATES PATENT OFFICE.

JAMES C. MILLER, OF PITTSBURGH, AND ANDREW ISLES, OF SWISSVALE, PENNSYLVANIA, ASSIGNORS TO THE W. R. MILLER COMPANY, A CORPORATION OF PENNSYLVANIA.

GAS PRODUCER.

Original application filed June 14, 1919, Serial No. 304,323. Divided and this application filed December 9, 1919. Serial No. 343,525.

To all whom it may concern:

Be it known that we, JAMES C. MILLER and ANDREW ISLES, citizens of the United States, and residents of Pittsburgh and 5 Swissvale, respectively, in the county of Allegheny and State of Pennsylvania, have made a new and useful Invention in Gas Producers, of which the following is a specification.

10 This invention relates to gas producers and more particularly to that type of producer having a revolving body portion.

This application is a division of our application filed June 14, 1919, Serial No. 15 304,323, which matured into Patent No. 1,373,443 on April 5, 1921.

An object of this invention is to provide continuously operating means for automatically removing the clinker which forms 20 along the inner surface of the revolving body portion of the producer.

This, as well as other objects which will readily appear to those skilled in the producer art, we attain by means of the device 25 described in the specification and illustrated in the drawings accompanying the same and forming a part of this application and throughout which similar elements are denoted by like characters.

30 In the drawings, Figure 1 is a sectional elevation of a portion of a gas producer embodying this invention, Fig. 2 is a top plan view on a reduced scale of the portion shown in Fig. 1 and Fig. 3 is a cross sectional view of the clinker grinder.

The producer proper consists of a cylindrical shell or body portion built up in any suitable manner and as shown in the drawings consists of an outer steel shell 6 and a brick lining 7 supported on an angle 40 8. The body portion is provided with a water-seal trough 9 at its top into which a depending annular flange 10 formed on top plate 11 projects. The top plate or cap 11, 45 which is stationary, is supported from the operating floor 12 of the producer house by means of suitable supporting feet 13 formed in any suitable manner.

Body 6 is provided with a support ring 50 14 adjacent its center and this ring is adapted to rest on suitable support rollers (not shown) carried in suitable standards (not shown) arranged around the producer. Ring 14 is provided with gear teeth 15 in

its outer periphery and through these the 55 body is adapted to be rotated.

The top of plate 11 is provided with an opening 16 surrounded by an upwardly extending annular flange 17 and a downwardly extending annular flange 18 and the 60 combined inner bores of these two flanges is preferably tapered as shown in Fig. 1. Through this tapered bore a clinker grinder 19 extends. The clinker grinder consists of a lower grinding portion 20 which lies in 65 close proximity to the inner surface of the revolving body of the producer and is preferably fluted on its outer surface as shown in Fig. 3 and hexagonal internally. The upper extremity of the lower portion at 21 70 is preferably cylindrical and fits with a drive or shrink fit into the lower portion of the upper part of the clinker grinder, which upper part is preferably externally tapered 75 as shown in Fig. 1 to correspond to the inner taper of the flanges 17 and 18.

A flange 22 extends around top plate 11, forming therewith a water pan. Near opening 16, the flange is continued around the opening in a small circle concentric therewith and the top of the flange is machined to form a race for balls 24. Bolted or otherwise secured to the upper part of the clinker grinder is a plate 23 from which an annular flange 34 depends, and, extending 80 into the water pan formed by flange 22 and top plate 11, cooperates therewith to form a seal for the clinker grinder. Plate 23 on its under side is provided with a race for balls 24. Plate 23 also carries a gear 25 which meshes with a gear 45 carried on a horizontal shaft 26 and which, by means of gears 27, 28, 29 and 30 is driven from a suitable operating motor. The gears just 85 described are so proportioned and arranged 90 as to rotate the clinker grinder in the same direction as the direction of rotation of the body of the producer but at a greater peripheral speed so as to tear, fracture, grind or crush and remove clinkers from the viscous clinker mass formed on the inner side 95 of the brick lining 7 as the rotating body moves past the clinker grinder. Cooling water is supplied to the interior of the clinker grinder through a depending pipe 100 31 and rising up around this pipe overflows through a port 32 into the water-seal surrounding the top of the clinker grinder.

In the present operation of gas producers, it is necessary to shut down the producer every week or oftener for the purpose of cleaning the walls of clinker accumulations. 5 The periods between cleanings depend upon the quality of coal used. The use of my invention eliminates the delay and other expense due to this shutdown and work.

In accordance with the provisions of the 10 patent statutes we have described the principle of the operation of our invention, together with the device which we now consider to represent the best embodiment thereof, but we desire to have it understood 15 that the device shown is only illustrative and that the invention can be carried out in other ways.

Having thus described our invention what 20 we claim as new and desire to secure by Letters Patent is—

1. In a gas producer having a revolving body portion and a stationary top, a hollow clinker grinder extending through said top and into the body portion adjacent its inner 25 surface and provided with a fluted grinding portion, a water seal for said clinker grinder, and means for rotating the grinder in the same direction as the body portion but at a different speed to provide grinding 30 action on matter between said body portion and said grinder.

2. In a gas producer, a rotating, cylindrical body, a rotating member spaced from the inner wall of said body and adapted 35 to co-operate therewith to grind clinkers formed on or adjacent said wall.

3. In a gas producer, a rotating body, a corrugated member positioned within said body adjacent the inner wall thereof and 40 means for rotating said member in the same

direction as said body but with greater peripheral speed whereby a portion of any substantial clinker mass, formed on said wall, as it contacts with said member is cut or torn away from the mass and said wall. 45

4. The method of preventing the accumulation of clinkers on the interior wall of a gas producer having a rotating body which consists in rotating a roughened element in close proximity to said wall while the producer is operating so as to grind the clinker mass adhering to the producer wall. 50

5. The method of preventing the accumulation of clinkers on the interior wall of a gas producer which consists in providing a 55 roughened element in close proximity to the wall and providing relative surface movement between said element and the wall without bodily movement of said element from said wall so as to continuously grind 60 the clinker mass adhering to the producer wall.

6. In a gas producer, a body, a member positioned within said body and provided with a corrugated surface adjacent the inner 65 wall of said body, means providing for bodily movement of said member relative to said body wall and means providing relative surface movement between the inner wall of said body and the corrugated surface of said 70 member whereby any clinker mass on the inner wall of said body is ground by the movements of the member relative to the body wall.

In testimony whereof, we have hereunto 75 subscribed our names this 1st day of December, 1919.

JAMES C. MILLER.
ANDREW ISLES.
